United States Patent Office.

CHARLES SPIRO, OF NEW YORK, N. Y.

Letters Patent No. 96,844, dated November 16, 1869.

IMPROVEMENT IN WATCH-WINDING AND SETTING ATTACHMENT.

The Schedule referred to in these Letters Patent and making part of the same.

To all whom it may concern:

Be it known that I, CHARLES SPIRO, of the city, county, and State of New York, have invented a new and useful Improvement in Winding and Setting-Attachment for Watches; and I do hereby declare that the following is a full, clear, and exact description thereof, which will enable others skilled in the art to make and use the same, reference being had to the accompanying drawings, forming part of this specification.

The object of this invention is to provide a permanent attachment to the post of the fusee or barrel, whereby the watch may be both wound and set; and

The invention consists in the combination and arrangement of parts for effecting the result.

Figure 1 represents a plan view of a watch, provided with my improvements, when opened at the back;

Figure 2 represents the same with the cap shut down;

Figure 3 represents a side elevation of a part of the movement when detached from the case; and

Figure 4 represents a similar view partly sectioned.

The upper end of the fusee-shaft is provided with a ratchet-clutch, *a*, permanently attached to it, and a hollow drum or sleeve, *b*, is placed on this clutch *a*, so as to slide up or down on it.

The said drum carries a spring, *c*, which, falling into grooves in the clutch, will hold it either up or down, as it may be placed.

The said drum also carries, at the lower end, a toothed wheel, *d*, and at the upper end, a ratchet, *f*.

The folding handle *g g'* is also attached to the upper end, the part *g* being crooked and connected by a pin passing through the sleeve and the ratchet *f*, and

the part *g'* is notched in the side and jointed to the upper end of the part *g*, both being provided with openings, suited in shape and arrangement to permit the parts to be folded down, as represented in figs. 1 and 2, into a recess in the cap.

When the attachment is pressed down into the position represented in fig. 1, the clutches are in gear with each other, and the wheel *d* is disconnected with the wheel *h*, which belongs to the train connecting with the hands. In this position, the handle *g g'* is turned back and forth, imparting an intermittent motion to the fusee, the clutches slipping at each return-motion.

When the attachment is adjusted to the position shown in fig. 4, the clutches are disengaged and the wheels put into gear for adjusting the hands.

The object of the spring *c* is to hold the attachment in either position, with sufficient strength to prevent it being inadvertently moved out of place while working, either for winding or setting.

By reason of the double connection of the handle *g g'*, it folds nicely into the circular hold in the cap, around the post required for turning the said handle.

Having thus described my invention,
I claim as new, and desire to secure by Letters Patent—

The combination of fusee-post, fixed and movable clutch-sleeve *b*, and arranged for winding and setting the watch, substantially as described.

The above specification of my invention signed by me, this 27th day of July, 1869.

CHARLES SPIRO.
